UNITED STATES PATENT OFFICE.

ROY F. HURLEY, OF GALESVILLE, WISCONSIN.

STERILIZING HOLDER FOR TOOTHBRUSHES.

1,364,557.

Specification of Letters Patent.

Patented Jan. 4, 1921.

Application filed February 28, 1920. Serial No. 362,066.

To all whom it may concern:

Be it known that I, Roy F. HURLEY, a citizen of the United States, residing at Galesville, in the county of Trempealeau and State of Wisconsin, have invented a new and useful Sterilizing Holder for Toothbrushes, of which the following is a specification.

My invention has for its purpose to provide a simple, neat and economical tooth brush holding device that is especially designed for rendering sterile the tooth brush, when placed therein, and in which the brush may be quickly placed after use and as quickly removed therefrom, when it is desired to use the brush.

My invention comprises, essentially, a box or holder body that includes an elongated hollow extension into which the brush handle is readily entered, an enlarged or head portion for receiving the bristle head of the brush and a removable cap for engaging with the outer end of the handle receiving extension that has an attached means for containing an antiseptic gas generating substance, a cap for the brush head receiving end being also included, which latter, in connection with the antiseptic substance holder keeping the said holder closed air tight, when the brush is contained therein.

In its more subordinate features, my invention embodies means within the holder for keeping the brush firmly in place and against rattling, while carrying the box or holder, other details of construction being also embodied in the complete arrangement of my brush holding device, all of which will fully appear in the following detail description, specifically pointed out in the appended claim and illustrated in the accompanying drawings, in which:

Figure 1 is a perspective view of my brush holding device and illustrates the manner in which the brush is inserted therein.

Fig. 2 is a longitudinal section thereof with a brush contained therein.

Fig. 3 is a plan view of the device, parts being in horizontal section.

Fig. 4 is a cross section of the same, on the line 4—4 of Fig. 2.

Fig. 5 is a detail view of the combined closure cap and antiseptic or gas generating substance holder.

In the practical development of my invention, the body 1 of the holder is preferably made of hard rubber, although it may

be made of aluminum or other suitable material.

The said body 1 is in the nature of a box-like receptacle that includes a head portion 2 open at the outer end and shaped for conveniently receiving the bristle or head portion of the brush 4 and to provide an air tight closure of the said end, the said brush head receiving portion includes a cap 3 that is hinged at the front edge of the part 2, the meeting faces of the parts 2 and 3 being preferably at an incline, as shown, and for holding the said faces closed air tight, a leaf spring 5 is attached, by a rivet 6, to the inner side of the top 30 of the box portion 3, the free end of the said spring 5 being curved and extended for engaging with a companion spring 8 that is riveted to the inside of the top portion 20 of the part 2, the free end of the two springs mentioned being so shaped and adapted for effecting a tight closure of the cap 3, when the latter is swung down to the closed position, as is clearly shown by full lines in Fig. 2, and for holding the said cap at the turned up or open position, as indicated in dotted lines in the aforesaid Fig. 2.

9 designates a shank-like extension of the box or body and the said shank merges with the part 2 and is of a reduced area and so shaped, in cross section, see Fig. 4, that it will snugly receive the brush handle, see Fig. 2, and for holding the brush against rattling within the holder, a curved leaf spring 10 is riveted to the bottom of the brush shank receiving portion of the holder and with its free end 11 curved upwardly, with respect to the head portion 2 of the box-like receptacle, whereby to constitute a guide-way or restricted passage for entering the shank of the brush, as it is inserted into the holder, in the manner clearly indicated in Fig. 1 of the drawings, and to thereby hold the said brush shank spring 100 pressed against the top portion 20 of the receptacle to secure the brush from rattling within the receptacle or holder, such securing of the brush being further provided for by projecting the free end of the spring 8, before referred to, so as to position it over the top of the brush head, when the latter is placed, as indicated in dotted lines on Fig. 2, it being obvious that the connection of the spring members 8 and 5, that constitute the lock for holding the cap 3, to its opened or closed position, operate to firmly hold the

brush down toward the bottom of the box 2, when the cap is swung down to the closed position in the said Fig. 2.

The end of the extension 9 is somewhat 5 enlarged and terminates in a circular chamber 12, the outer end of which is internally threaded, as at 13, for receiving the threaded screw cap 14 of a container 15, the latter, when screwed home, as indicated in Figs. 2 10 and 3, serves as an air tight closure means for that end of the holder.

The container 15 is in the nature of a perforated cylinder, the inner end of which is closed by a perforated disk 16 that is 15 movably held within the said end of the cylinder in any suitable manner.

The outer or cap end of the container is provided with a hinged bail for hanging the sterilizer, when not in use, and to facilitate 20 unscrewing the cap, the latter may be provided with a transverse groove, as indicated at 14^a in Figs. 4 and 5, for the insertion of a dime or knife blade.

Cylinder 15 is provided for receiving any 25 suitable material, asbestos or bibulous paper, adapted for receiving a saturating solution, the gas of which, when the holder is kept closed and air tight, will render sterile the tooth brush contained within the holder.

From the foregoing description taken in 30 connection with the drawings, the complete construction, the manner of use and the advantages of my invention will be readily apparent to those familiar with the use of

brush holding devices of the class to which 35 my invention relates.

What I claim is:

A device of the character described comprising a receptacle in which is included a restricted hollow extension adapted for receiving the shank of a tooth brush and having its outer end shaped for receiving a disinfectant holder, the other end of the receptacle being formed into an enlarged chamber adapted for receiving the head of 45 the brush, a leaf spring that is secured at one end to the bottom of the restricted hollow extension and whose free end is upwardly curved, whereby to form a restricted opening for the passage of the tooth brush 50 shank, between it and the top of the restricted chamber, and adapted to engage the neck end of the brush handle to hold the said handle in contact with the said chambered top and the brush from rattling, the said 55 brush head receiving chamber being open at the outer end, a closure cap for such opening, said cap being hingedly connected to swing outwardly from the head receiving chamber, and means for holding the cap to 60 its opened and closed positions, the said means including a leaf spring member that opposes the spring member secured to the bottom of the hollow extension of the holder and which is projected for positioning over 65 the brush head, when the latter has been pushed into the holder.

ROY F. HURLEY, D. D. S.
